CLAIM

The ornamental design for a swivel bayonet sewer fitting, as shown and described.

DESCRIPTION

FIG. 1 is a top, right front perspective view of a swivel bayonet sewer fitting embodying our design;

FIG. 2 is a bottom, right front perspective view of the same invention in FIG. 1;

FIG. 3 is a front side elevational view thereof, the rear side elevational view being a mirror image;

FIG. 4 is a right side elevational view thereof, the left side elevational view being a mirror image;

FIG. 5 is a top plan view thereof; and,

FIG. 6 is a bottom plan view thereof.
